UNITED STATES PATENT OFFICE

ERNEST J. LIEBETRAU, OF NILES, MICHIGAN, ASSIGNOR TO THE KAWNEER COMPANY,
OF NILES, MICHIGAN, A CORPORATION OF MICHIGAN

WINDOW CONSTRUCTION

Application filed July 14, 1930. Serial No. 467,772.

The present invention relates to window constructions, and more in particular to a novel window construction provided with a drop sash adapted to be lowered to its open positions.

Among the objects of the present invention is to provide a novel metallic sash construction adapted to be slidably positioned in a window frame and to form therewith a weather-tight closure whenever the sash is in closed position.

A further object of the invention is to provide a novel metallic frame construction adapted to receive a sash member and permit sliding movement of the same. The invention comprehends the use of catch means or mechanism mounted on the interior of the window sash adjacent the top thereof, such catch mechanism being provided with plungers adapted to seat in openings in the stiles of the window frame so as to hold the sash in various positions of adjustment. The frame also comprehends the provision of a well or pocket in the bottom thereof for the reception of the sash when the same is in an opened position.

A still further object of the invention is the provision of a unitary frame construction in which the sash may be mounted at the factory, and the entire assembly of the window frame unit completed thereat, so that the unit may be shipped to its destination, and readily applied to a building opening or the hull of a ship.

A further object of the invention is the provision of weather-tight sealing means for providing a weather-tight seal between the sash and frame when the sash is in closed position. Provision is further made for the drainage of any liquid or other foreign matter which may enter the well or pocket in the lower part of the frame. In the present embodiment in which the window construction is shown as applied to a ship, drainage means are provided from the lower portion of the pocket or well to the exterior of the hull of the ship so that any foreign matter which may collect in the pocket or well may readily drain or be removed therefrom.

Further objects of the invention are to

provide a construction of maximum simplicity, efficiency, economy and ease of assembly, maintenance and operation, and such further objects, advantages and capabilities as will later more fully appear, and are inherently possessed thereby. 55

The invention further resides in the combination, construction and arrangements of parts illustrated in the accompanying drawing, and while I have shown therein a preferred embodiment, it is to be understood that the same is susceptible of modification and change without departing from the spirit of the invention.

In the drawing:

Fig. 1 is a view in side elevation of the exterior of the window sash and frame construction.

Fig. 2 is a view in vertical cross section taken in the plane represented by the line 2—2 70 of Fig. 1.

Figs. 3 and 4 are horizontal cross sections taken in planes represented by the lines 3—3 and 4—4, respectively, of Fig. 1.

Fig. 5 is a fragmentary view in side elevation of the upper corner of the sash construction.

Referring more particularly to the disclosure in the drawing, the numeral 1 designates the hull or metal plate of a ship structure 80 provided with an opening in which is mounted a window frame designated generally as 2 and provided with a slideable sash 3.

The frame 2 comprises a sill consisting of an interior section or plate 4 and an exterior section 5, a head jamb 6, and stiles 7 and 8. Connected to the head jamb 6 and the section 5 of the sill, as by means of rivets, bolts or the like 9, are provided an upper metal trim 10 and a lower metal trim 11, which are 85 suitably connected to the hull or metal plate of the ship. Likewise, the metal trim 12 is connected on the interior to the stiles 7 and 8 by means of a channel or groove portion, these sections 12 of metal structure being disclosed as connected to the frame or metal plate 1 of the ship, as by means of bolts, screws or the like 14. The interior portion 4 of the sill is mounted upon a stool 15 and may be 90 connected thereto by any suitable means. 95

The head jamb 6 contactingly engages a head piece 16 of the interior wood trim and may be connected thereto as by means of screws or the like. The stiles 7 and 8 are shown as being connected to the side jambs 16 of the wood trim by means of the screws or the like 17.

The lower portion of the window frame 2 is shown as provided with a well or pocket 17 adapted to receive the sash 3 when the same is in open position. As disclosed in Figs. 2 and 4, the stiles 7 and 8 extend to the bottom of this pocket or well 17, the stiles being provided with a U-shaped groove or channel 18 adapted to receive the side rails 19 of the sash construction. These side rails are provided with an outwardly extending doubled-over portion to provide a tongue or rib 20 seating within and slidably engaging in the U-shaped grooves or channels 18. The head jamb 6 is provided with a horizontally extending U-shaped groove or channel 21 similar to the channels 18 in the stiles, the same being adapted to receive the doubled-over portion or rib 22 of the top rail 23. The side rails 19 and the top rail 23 are similar in construction, each providing a channel member, the same being very similar in construction to the bottom rail 24, with the exception that this bottom rail is not provided with a doubled-over portion or rib adapted to seat within a groove for permitting sliding engagement or for permitting a weather-tight closure. Each of the rails is provided with a reinforcing bar 25 extending throughout the length of the rails and fitting conformably therein.

Channel-shaped sections of felt or the like 26 are provided in the rails adjacent the reinforcing bars, so as to permit expansion of the glass along with slight yielding movement thereof.

In order to provide a weather-tight closure adjacent the bottom rail when the sash is in closed position, such rail is provided with a strip of rubber or the like 27 having an inclined face 28 adapted to seat against an inclined face on the exterior member 5 of the sill. This strip may be attached to the rail by means of bolt screws or the like 29, or by means of clips. Latch mechanism 30 is provided on each of the side rails adjacent the top of the sash. Each of the catch or latch mechanisms are provided with a plunger adapted to seat in openings suitably spaced in the stiles 7 and 8 so as to maintain the window in closed position, or in various open positions.

As disclosed in Fig. 5, the top rail 23 is removable from the remainder of the sash construction in order to permit efficient glazing of the sash. As disclosed, the side rails 19 and the top rail 23 are cut on a bias at 31, as likewise are the reinforcing bars 25 inserted therein. Bolts or the like 33 are passed

through the top rail, and reinforcing bars, holding the top and side rails in position, but permitting the removal of the top rail by removal of the bolts 32, one of which is provided adjacent either end of the top rail.

Since the wall or pocket 17 is open to the elements whenever the sash is in lowered position, drain members 32 are provided adjacent the bottom of the wall or pocket 17 and draining therefrom to the exterior of the hull of the ship. Thus any liquid or any foreign matter collecting therein will drain from the pocket or well.

From the above disclosure and the embodiment illustrated in the drawing, it will be readily seen that I have provided a novel construction of drop window and frame therefor, which can be readily constructed as a unit and easily assembled within a building opening and maintained. Although I have disclosed the invention as particularly applicable to a ship construction, it will be readily seen and understood that the same is admirably adapted for other uses and constructions.

Having thus disclosed my invention, I claim:

1. A unitary metallic window construction for a ship adapted to be bodily mounted in an opening in a side thereof, comprising a frame including a head jamb, stiles and sill, a trim connected to said head jamb, stiles and sill and to the exterior of the ship, a well provided in the lower portion of the frame, and a slideable sash adapted to be lowered into the well for opening the window.

2. A unitary metallic window construction for a ship, comprising a frame including a head jamb, stiles and sill, a trim connected to said head jamb, stiles and sill, and to the exterior of the ship, a channel formed in said head jamb and stiles, a well provided in the lower portion of the frame, and a sash slideable in said channels and adapted to be lowered into the well for opening the window.

3. A unitary metallic window construction adapted to be completely assembled at the factory ready for mounting, comprising a frame including a head jamb, stiles and sill, an offset channel formed in said head jamb and stiles, a well provided in the lower portion of the frame, and a sash having top and side rails provided with a rib seating in and slideable in said channels and adapted to be lowered into the well for opening the window.

4. A unitary metallic window construction adapted to be completely assembled at the factory ready for mounting, comprising a frame, including a head jamb, stiles and sill, a channel formed in said head jamb and stiles, a well provided in the lower portion of the frame, and a sash member provided with offset ribs adapted to seat within and be guided in the channels of the frame.

5. A unitary metallic window construction adapted to be completely assembled at the factory ready for mounting, comprising a frame including a head jamb, stiles and sill, offset channels formed in said frame, a well provided in the lower portion of the frame, and a sash provided with offset ribs seating in and slideable in said channels and adapted to be lowered into the well for opening the

10 window.

6. A unitary metal window construction adapted to be completely assembled at the factory ready for mounting, comprising a frame including a head jamb, stiles and sill, 15 a channel formed in said head jamb and stiles, a well provided in the lower portion of the frame, and a sash adapted to be lowered into the well, said sash being provided with upper, lower and side rails, the upper 20 and side rails being provided with a rib adapted to seat in the channels for sliding movement of the sash, and the lower rail being provided with a weather strip adapted to wedgingly engage the sill when the sash is 25 in closed position.

In witness whereof, I hereunto subscribe my name to this specification.

ERNEST J. LIEBETRAU.
